UNITED STATES PATENT OFFICE.

HAROLD W. HODGETTS, OF SPRINGFIELD, MASSACHUSETTS, ASSIGNOR TO LEON J. HARLEY, JR., OF SPRINGFIELD, MASSACHUSETTS.

CASKET-BOX HANDLE.

1,319,339.

Specification of Letters Patent. Patented Oct. 21, 1919.

Application filed March 29, 1919. Serial No. 286,081.

To all whom it may concern:

Be it known that I, HAROLD W. HODGETTS, a citizen of the United States of America, residing at Springfield, in the county of 5 Hampden and Commonwealth of Massachusetts, have invented certain new and useful Improvements in Casket-Box Handles, of which the following is a specification.

This invention relates to improvements in 10 handles for caskets, or other box-like structures, and particularly it relates to the manner of constructing the base or socket plate and the handle which is pivotally attached thereto so as to fold into the plane of the 15 plate. Broadly considered, my invention comprises a plate which may be termed the base or socket plate, the socket portion of which is formed by slitting the plate from one edge a suitable distance, then bending 20 inward a portion of the plate, the bent-in portions serving as attaching means for pivotally securing the handle to the plate and in the openings formed by the bent-in portions. The pivotal connection in the present 25 invention comprises two fixed pins, one serving as the center about which the handle turns and the other serving as a limiting stop for the upward movement of the handle. In the construction of this class of 30 handles, as they are at present formed, the upward or limiting movement of the handle often acts on a single pivot and with the upper surface of the handle engaging the lower edge of the opening in the base-piece, 35 with the result that breakage of the handle attaching means often occurs. In the present invention the two pins serve to receive the entire weight placed thereon, one of the pins serving as a pivot and the other as 40 a limiting stop for the upward movement of the handle. The invention will be fully described in the specification and particularly pointed out in the claims.

Referring to the drawings:

Figure 1 is an elevational view of the 45 finished structure showing the exterior surface of the same, and with the handle in a closed or lowered position.

Fig. 2 is a view of Fig. 1 looking at the 50 interior of the structure and showing the two pins for attaching the handle to the base plate.

Fig. 3 is a horizontal sectional view on the 55 line 3—3 of Fig. 1 showing one of the cotter pins for attaching the handle to the base-

plate and also illustrating the bent-in or struck-up portions of the plate and extending inward to a point coinciding with the bearing surface of the plate for forming a bearing and also forming the sockets or 60 openings for the handles.

Fig. 4 is a vertical sectional view on the line 4—4 of Fig. 2 showing the handle in full lines in its closed or lowered position and in dotted lines in its elevated or lifted position and illustrating the locked position of the handle by means of pin construction.

Fig. 5 is a perspective view of one end of the structure and showing in detail the construction of the base-plate and a portion of 70 one end of the handle spaced from the base-plate and illustrating the curved slot in the ends of the handle which receives one pin and the opening to receive the pivotal pin.

Referring now to the drawings in detail: 75 1 designates the base or socket plate which is attached to the side of the casket or other box-like structure. This plate is preferably formed from sheet metal of suitable thickness. This plate, as shown, is formed with 80 a curved border or edge indicated at 2, and which bears directly against the outer supporting surface of the casket. 3 indicates openings for receiving attaching screws. The plate 1 is formed with the openings or 85 sockets at its ends 4 as shown in Figs. 1 and 2. One of the openings is shown in Fig. 5. This opening is preferably formed by means of dies or punches which first cut a slit in the metal as indicated by the dotted line 5 in Fig. 5. At the same time the pivot pin receiving openings 6 and 7 are formed or punched. The next operation of the dies or punches is to bend a portion of the base-plate adjacent the slit 5 downward or in- 90 ward, as indicated by the arrows 8, and into the full line position shown in this figure, thus forming the handle-attaching ears 9 and 10. The distance below the outer sur- 95 face of the plate 1 which these ears or pro-jections extend is preferably equal to the height of the plate 1 as shown in Fig. 3 by the line 11, which line indicates the bearing surface against which the plate 1 rests. It is of course obvious that the length of the 100 ears or extensions 9 and 10 may be less than the height of the base-plate.

Referring to the construction of the handle proper, 12 indicates the ends of the same which are formed with the bent-down por- 110

tions 13 and 14 which are preferably made by stamping a piece of sheet metal of suitable thickness. Before the sides of the handle are bent downward, the openings 15 and 5 16 are formed. The opening 15 is the pivotal opening for the handle, while the opening 16 is an arc-shaped slot through which the limiting pin passes, which pins are usually cotter pins as shown at 17 and 18. The 10 closed position of the handle is shown in Figs. 1, 2 and 4 in full lines and in dotted lines in Fig. 4 it is shown open in which the pin 18 is engaging the end of the curved slot which serves as a limiting stop when the 15 handle is lifted to the dotted position shown. The two pins 17 and 18 will thus serve to receive the full load that is placed upon the handle. If desired, the edge 19 of the 20 socket, (see Fig. 5) may also be used to receive a portion of the load when the handle 12 is lifted, and thus prevent a possible breakage of either one or both of the pins.

It will be noticed that this construction is extremely simple and easy to manufacture 25 and at a small cost as all of the operations may be made by punch or press work; that the plate 1 is made from a single piece of metal, and that the handle 12 is also made from a single piece of metal and suitably 30 formed by means of a die or press.

It is to be understood that the openings 15 and 16 in the handle 12 are formed before the portions 13 and 14 are bent inward as shown in Fig. 5.

35 It is understood that when the plate 1 is secured to the casket or casket-containing box the inner edges of the ears 9 and 10 will bear against the supporting surface and thus prevent the plate from being 40 crimped or bent inward. I do not, however, limit myself to making these ears of any particular length, as they may be made shorter than those shown. It will be noticed that the openings 6 and 7 of the ears 9 and 45 10 are equally spaced from the outer face of the plate 1.

What I claim is:

1. In a device of the kind described, the combination with the base or plate-member 50 composed of a single piece and formed with cut out or socket portions, the borders of the openings having integral inwardly extending ears with a pair of openings in each ear in alinement with each other, the 55 depth or length of the ears being equal to the depth of the base-plate to serve as a support or bearing for the base-member, a handle formed from a single piece of metal and with bent end portions and located in 60 the cut-out or socket portions and pivotally attached thereto by means of a pair of pins, pivotal openings in the bent-end portions of the handle, one of which is arc-shaped and the other circular, whereby the arc-

shaped openings will serve as a limiting 65 stop for the upward movement of the handle, as described.

2. In a handle-structure for caskets and comprising, in combination, a base-plate formed from a single piece of metal and 70 having a curved border or edge which bears against the supporting surface to which the handle is attached, said base-plate having two pairs of inwardly extending integral portions or projections with openings in 75 alinement therein for receiving handle supporting pins, said portions being bent at an angle to the base piece to form openings or handle receiving sockets, means for attaching a handle in the openings in the base-piece and comprising two pins located in the openings of the inwardly extending portions, said handle having inwardly extending one piece projections and pintle receiving openings therein, some of said openings 80 being arc-shaped to limit the upward movement of the handle.

3. In a casket handle structure, a single piece metal plate formed with openings 90 therein struck up from the metal of the plate, the struck up or bent portions having openings, said openings being designed to receive a handle having bent-end portions that are formed by bending the ends of the handle toward each other in parallel position to form rectangular shaped ends, which fit into the openings in the plate, said ends having a pivotal opening and an arc-shaped opening for receiving the handle attaching pins, and the upper border of the opening 95 in the base-piece serving as a stop for the upward movement of the handle together with one of the pins engaging the end of the arc-shaped slot, as described.

4. A casket handle structure comprising, 100 in combination, a base-plate formed with openings, the opposite sides of which are provided with plates or projections struck up from the base-plates, and each having two openings spaced the same distance from 105 the face of the base-plate, a one piece handle member, the inner ends of which are provided with parallel sides, each having two 110 openings, one being arc-shaped, to receive pins for attaching said member to the projections and for limiting the upward movement of the handle.

5. In a casket handle structure, a base-plate formed from a single piece of metal, 115 means for attaching a handle member proper thereto and for limiting the upward movement of the same, and comprising pairs of 120 projections on said plate spaced from each other and formed with openings there-through, said member having ends for entering the space between the projections and 125 openings in its ends to receive pins which are placed in the openings of the projec-

tions, some of the openings in the ends of the member being arc-shaped to limit the upward movement of the handle member when the pin reaches the end of the arc-shaped slot.

- 5 6. A casket-handle structure comprising a base plate formed from a single piece of metal, projections struck up from the same to form openings in the face of the plate
10 for attaching the handle member proper to the plate, the member and projections having two pairs of alining openings to receive pins, two of the openings in the member being arc-shaped to limit the movement of
15 said member.

7. A casket box handle comprising a plate formed from a single piece and having

struck-up marginal bearing edges, and cut-out portions, the opposite marginal edges of said portions having integral inwardly extending projections of a length equal to the 20 depth of the struck-up marginal edges from the body or central portion of the plate to serve as a support for the central portion of the plate, a handle formed from a single piece of metal with bent-end portions and 25 located in the cut-out portions, two pins passing through openings in the projections of the plate and handle, for attaching the handle to the plate, one of the openings in the handle being arc-shaped to limit the up- 30 ward movement of the handle, as described.

HAROLD W. HODGETTS.
